UNITED STATES PATENT OFFICE.

JOHN F. TUDOR, OF WILMINGTON, OHIO, ASSIGNOR OF ONE-FOURTH TO GROVER C. KESSINGER AND ONE-FOURTH TO CHARLES N. SECRIST, BOTH OF WILMINGTON, OHIO.

RAILROAD-TIE.

1,098,996.

Specification of Letters Patent. Patented June 2, 1914.

Application filed February 6, 1914. Serial No. 316,981.

To all whom it may concern:

Be it known that I, JOHN F. TUDOR, a citizen of the United States, residing at Wilmington, in the county of Clinton and State of Ohio, have invented certain new and useful Improvements in Railroad-Ties; and I do hereby declare the following to be a full, clear, and exact description of the invention, such as will enable others skilled in the art to which it appertains to make and use the same.

This invention relates to new and useful improvements in railway ties, and has for its principal object the provision of a tie which will prevent the rail from spreading, sinking or creeping.

Another object of the invention is the provision of a tie in which the resilient qualities of the old type of wood tie are retained and combined with the advantages which are present in the use of a metallic tie.

A further object of the invention is to provide a simple and effective means for securing the rail in place on the tie and preventing the same from becoming displaced.

Still another object of the invention is to provide a concrete tie in which the material will be considerably reinforced and thereby the strength of the tie will be materially increased.

With the above and other objects in view, the invention consists in the novel combination and arrangement of parts which will be fully set forth in the following specification and accompanying drawings, in which—

Figure 1 is a view of a tie constructed in accordance with this invention showing the same partly in section to more clearly illustrate the reinforcement bars, Fig. 2 is a top plan view of a tie constructed in accordance with this invention, and Fig. 3 is a transverse sectional view taken on line 3—3 of Fig. 1. Fig. 4 is an enlarged detail, longitudinal, sectional view of a fragment of the tie to more clearly illustrate the nut lock and rail clamp.

Referring now to the drawings by characters of reference, the numeral 1 designates as an entirety, a railroad tie constructed in accordance with this invention which comprises the plastic body portion 2 which is formed of concrete or a similar material.

This body portion 2 is provided near each end with a recess 3 in which the wood bearing block 4, forming a rail seat, is adapted to rest. A plurality of longitudinally extending, reinforcing bars 5 are embedded in the plastic material and extend parallel with the bottom of the tie. A plurality of long bowed steel rods 6 are also embedded in the concrete and extend substantially throughout the entire length of the tie. 65 These rods 6 are bowed upwardly at their center, and are arranged to receive any vertical strain to which the tie might be subjected. A plurality of bowed reinforcing elements 7 which are of less length than the 70 reinforcing members 6, are also provided and are adapted to coöperate with the before-mentioned reinforcing bars in taking up the lateral strain against the tie. These bars 7 are bowed as illustrated in Fig. 1 75 and are of substantially half the entire length of the tie, thus adding considerably to the strength of the tie at its center and preventing the same from cracking or becoming injured in any way. Near each end of the tie is provided a pair of transverse apertures 8 which extend vertically throughout the entire depth of the tie and are adapted to receive the bolts 9 by means of which the rail-securing elements 10 are held in 80 place.

Formed integral with each of the rail-securing elements 10 near the end opposite the flange engaging member is preferably provided the upstanding ear 11 having formed therein the aperture 12 through which the cotter pin 13 is adapted to extend. A suitable body portion 14 having formed thereon the ears 15 is provided, and each of the ears is provided with apertures through which the pin 13 is adapted to extend, and thus pivotally secure the body portion to the ear 11. The end of the body portion opposite the pivoted end is provided with the hexagonal aperture 16 which is arranged to receive the nut which cooperates with the bolt and prevents the same from becoming loosened. 95

It will be apparent from the foregoing that owing to the particular arrangement and construction of the reinforcing elements, the tie will be prevented from becoming cracked or broken since the strain is taken up by the bars 5, 6, and 7. It will also be apparent that the rails will be prevented 100 1 from being moved laterally.

from sinking since these bars are arranged to exert upward pressure against the rail, thus holding the same at the proper gage and preventing any depression and similar 5 undesirable results which might come from the tie cracking in the center and permitting the rails to drop.

Owing to the position and arrangement of the blocks 4, it will be apparent that any 10 road shocks will be absorbed thereby, and should said blocks become worn, they may be removed without in any way necessitating the loosening of the rail clamp. Thus it will be seen that a material saving in 15 labor will be made in the use of a tie of this construction.

While in the foregoing there has been shown and described the preferred embodiment of this invention, it is to be understood that such changes may be made in the combination and arrangement of parts as 20 will fall within the spirit and scope of the invention as claimed.

Having thus described my invention, I 25 claim:

1. A railroad tie comprising a plastic body portion, a plurality of reinforcing bars throughout substantially the entire length of the plastic body portion and parallel with 30 the bottom thereof, a plurality of long bowed reinforcing elements embedded in the body portion, a plurality of relatively short bowed reinforcing elements embedded in the plastic body portion, both the long 35 and the short reinforcing elements being arranged so that their greater length is above

the first-mentioned reinforcing elements to add strength to the center of the tie, means carried by the tie near each end to secure a railroad rail in place. 40

2. In a device of the character described, a plastic body portion, a plurality of reinforcing elements embedded in the body portion and extending substantially throughout its entire length, said reinforcing elements being parallel with the longitudinal walls of the body portion, a plurality of relatively short bowed reinforcing elements superposed and embedded in the plastic body portion above the first-mentioned reinforcing elements, the ends of the second-mentioned reinforcing elements terminating substantially beneath the inner edges of the point where the rail flanges rest, and a plurality of relatively long reinforcing elements, said long reinforcing elements being bowed at their center, and the central portions thereof superposed above the short bowed reinforcing elements, thereby strengthening the center of the tie and preventing the ends from sinking, and means to hold railroad rails firmly in place on the tie. 45 50 55 60

In testimony whereof I affix my signature in presence of two witnesses.

JOHN F. TUDOR.
